CAR ROOF

Charles David Bonsall, Pittsburgh, Pa., assignor
to P. H. Murphy Company, New Kensington,
Pa., a corporation of Pennsylvania

Application March 3, 1933, Serial No. 659,490

6 Claims. (Cl. 108—5.4)

It is quite common to load certain commodities, such as flour and cement, into freight cars, while they are still hot from the process of manufacture, with the result that the roofs of the cars sometimes "sweat" enough to cause considerable damage to such commodities. One of the principal objects of the present invention is to minimize such sweating. Other objects are to protect the lading from rapid changes of temperature and to design a construction of roof that will be economical of material and labor, of great strength and will have advantages hereinafter appearing.

The invention consists in the parts and in the arrangements and combinations of parts herein-after described and claimed.

In the accompanying drawing, which forms part of this specification, and wherein like reference numerals refer to like parts wherever they occur,

Fig. 1 is a plan view of a portion of a cellular car roof embodying my invention,

Fig. 2 is an enlarged vertical transverse section through one-half of the roof on the line 2—2 in Fig. 1,

Fig. 3 is an enlarged vertical longitudinal section through the roof on the line 3—3 in Fig. 1, and

Fig. 4 is a section similar to Fig. 3, illustrating an insulated web member.

The construction illustrated in Fig. 1 comprises an upper series of roof sheets or panels 1 that span from side plate 3 to side plate 3 of the car and a lower series of roof sheets or panels 2 which likewise span from side plate to side plate of the car, both series of sheets having their ends secured to said side plates. Interposed between the upper sheets 1 and the lower sheets 2 is a series of web members 4. In the design shown in Fig. 3, these web members are separate pieces of Z-form, that is, they are shown with a vertically disposed body portion having a horizontal flange 5 extending laterally from the top thereof and a flange 6 at the bottom thereof extending laterally in the opposite direction. These web members 4 extend from side plate to side plate of the car and have their ends secured thereto. The sheets 1 of the upper series are arranged in the same plane with their side edges somewhat spaced apart but fairly close together and resting upon the upper flanges 5 of the web members 4. Adjacent sheets 1 of the upper series are welded, as at 7, together and to the upper flange 5 of the adjacent web member 4. Such welding is preferably done electrically by means of a welding rod

which furnishes the material (preferably steel of high tensile strength) for filling out any space there may be between the parts that are being welded together.

The adjacent sheets or panels 2 of the lower series are similarly spaced apart and welded, as at 8, together and to the underside of the lower flange 6 of the web member 4. In practice, it is preferable to assemble the roof sheets 1 and 2 and web members 4 in jigs apart from the car 10 frame and weld them all together into a unitary construction which is applied as a unit to the car frame.

The roof above described is light and strong and its parts are very simple, easy and inexpensive to make. It is noted that the sheets 1 and 2 are plain flat sheets without any ribs or flanges, that they have no bolt or rivet holes, and do not require to be sheared to accurate width. It is also noted that the welds 7 and 8 are continuous, 15 watertight and stronger than the other parts of the sheets. The cellular structure of the roof, together with the welding thereof, not only gives it great strength but permits the use of relatively thin material. Besides, such cellular structure 20 gives the roof an insulating capacity which so greatly retards the transmission of heat therethrough as to make a car equipped with such roof suitable for handling commodities, like flour and cement, which are loaded hot and liable to 25 cause sweating. This is true, because "sweating" in the case of such commodities is occasioned by the relatively warm moisture laden air coming in contact with the cold roof. The conditions which produce sweating occur, for instance, when on a 30 cold, humid day the empty car is run inside a relatively warm building to be laden and is then promptly shifted to the outside. Due to infiltration, there is a continuous tendency for the humid air of the car to be replaced with the less humid 35 air from outside, and the roof will not "sweat" if the temperature of the lower roof sheets decreases more slowly than the decrease of humidity of the air inside the car. Thus, for such commodities as flour and cement, which are not sensitive 40 to freezing, the relatively inexpensive roof above described is as satisfactory as more thoroughly insulated roofs which are much more expensive.

In the construction above described, the web member 4 is a single piece of pressed metal. With 50 the web member made in a single piece, there is direct heat conduction between the inside of the car and the outside thereof. In order to interrupt such direct conduction, the web member may be made in two pieces 9 of angular form with 55

- their vertical portions wide enough to overlap and with a strip or layer of suitable insulation 10, such, for instance, as asbestos fiber, interposed between them, the two parts being secured together by welding or by horizontal bolts or rivets 11, as illustrated in Fig. 4. The interposition of this insulating material 10 greatly increases the insulating property of the roof as a whole and greatly prolongs the time required to 5 equalize the temperatures on the inside and the outside of the car. Thus, the use of such insulated web members fits the car for use in hauling many commodities that now require more expensive refrigerator cars.
- 15 Reference is hereby made to my copending applications Serial No. 27,524 filed June 20, 1935, and Serial No. 27,848 filed June 22, 1935, covering the subject matter as divided out of this application.
- 20 What I claim is:
1. A car roof comprising roof sheets arranged alongside of one another but somewhat spaced apart at an upper level and roof sheets arranged alongside of one another but somewhat spaced 25 apart at a lower level, Z-shaped members underlying the margins of adjacent upper sheets and overlying the margins of adjacent lower sheets and welds uniting the edges of adjacent sheets together and to said members.
  - 30 2. A car roof comprising roof sheets arranged alongside of one another at an upper level and roof sheets arranged alongside of one another at a lower level, members in contact with sheets of both levels, and welds uniting the sheets to said members, said members comprising an upper part and a lower part secured together with insulating material interposed between them.
  - 35 3. A car roof comprising roof sheets arranged alongside of one another but somewhat spaced apart at an upper level and roof sheets arranged alongside of one another but somewhat spaced apart at a lower level, Z-shaped members under-

lying the margins of adjacent upper sheets and overlying the margins of adjacent lower sheets and welds uniting the edges of adjacent sheets together and to said members, said members comprising an angular upper part and an angular 5 lower part arranged with their vertical legs lapsing and secured together with insulating material interposed between them.

4. A car roof constituting a self-supporting structure capable of application as a unit to the 10 side plates of a car, said roof comprising roof sheets arranged alongside of one another but somewhat spaced apart at an upper level and roof sheets arranged alongside of one another but somewhat spaced apart at a lower level, separate 15 web members of pressed metal with vertically disposed body portions with flat top portions extending laterally therefrom and spanning the spaces between adjacent sheets of the upper level and with flat flanged bottom portions 20 spanning the spaces between adjacent sheets of the lower level and welds uniting the edges of adjacent sheets together and to said members continuously from side to side of the roof.

5. As an article of manufacture, a web member 25 for cellular car roofs, said member consisting of three parts secured together, two of said parts being made of metal adapted for attachment to the top and bottom, respectively, of the cellular car roof and the third part being a strip of insulating material interposed between said metal parts.

6. As an article of manufacture, a web member 30 for cellular car roofs, consisting of three members secured together, two of said members 35 being metal members of angular form adapted for attachment to the top and bottom, respectively, of the cellular car roof and the third part consisting of a strip of insulating material interposed between them.
